UNITED STATES PATENT OFFICE.

WILLIAM McCONWAY, JR., OF PITTSBURGH, PENNSYLVANIA, ASSIGNOR TO THE
McCONWAY & TORLEY COMPANY, OF PITTSBURGH, PENNSYLVANIA, A CORPO-
RATION OF PENNSYLVANIA.

DRAFT APPLIANCE FOR RAILWAY-VEHICLES.

1,171,861.

Specification of Letters Patent.

Patented Feb. 15, 1916.

Application filed July 2, 1915. Serial No. 37,675.

To all whom it may concern:

Be it known that I, WILLIAM McCONWAY, Jr., a citizen of the United States, residing at Pittsburgh, in the county of Allegheny and State of Pennsylvania, have invented 5 certain new and useful Improvements in Draft Appliances for Railway-Vehicles; and I do hereby declare the following to be a full, clear, and exact description of the 10 invention, such as will enable others skilled in the art to which it appertains to make and use the same.

My invention relates to draft appliances for railway vehicles and more especially to 15 means for yieldingly retaining a car coupler in its normal position in the longitudinal axis of the car.

The principal object of the invention is to provide coupler centering devices which, 20 while efficiently controlling the lateral swinging movements of the coupler, shall be strong and durable and capable of being readily assembled and disassembled without the necessity of cutting any rivets and with- 25 out requiring the use of special tools.

The object of my invention, generally stated, is effected by slidably mounting on the stem of a car coupler having a pivoted coupler head a frame that is supported by a 30 longitudinally extending spring which is operatively interposed between the rear end of said frame and said stem, the frame having mounted upon it spring supported followers or spring-cups which are adapted to 35 reciprocate transversely and to contact the carry-iron or some other stationary abutment on the vehicle, said frame involving a bifurcated member having longitudinally extending slotted branches for the recep- 40 tion of the spring-cups, and a detachable member having interlocking engagement with said branches and forming a seat for the longitudinally extending spring by which the sliding movements of the frame 45 upon the stem are controlled.

In the drawings illustrating the preferred embodiment of my invention, Figure 1 is a plan view of a draft appliance embodying novel features hereinafter claimed, a portion 50 of the stem of the coupler being broken away and a portion of the coupler head being shown in horizontal section. Fig. 2 is a side elevation of the devices illustrated in Fig. 1. Fig. 3 is a vertical longi- 55 tudinal section of the construction. Fig. 4 is a transverse section, taken in the plane of the line 4-4, Fig. 1. Fig. 5 is a trans- 60 verse section taken in the plane of the line 5-5, Fig. 1; and Fig. 6 is a detail perspective view of elements of the slidable frame, illus- 65 trating their mode of assembly.

In the drawings, 1 indicates the coupler head and 2 is the coupler stem. As the mechanism illustrated in the drawings may serve to centralize the coupler head with 70 respect to the stem as well as to centralize the coupler as a whole, the coupler head 1 and stem 2 are preferably pivotally connected by means of a pivot pin 3 which passes through alined, correspondingly 75 formed apertures in the coupler head and in the forward end of the coupler stem. The coupler stem 2 may conveniently be of the well known bifurcated type having upper and lower plates or branches 4, 4 that are 80 rigidly united at their rearward ends. For the purpose of connecting the coupler to the railway vehicle so that it may move or swing laterally with respect thereto, the rear end of the coupler stem is preferably 85 provided with an aperture 5 which is adapt- 90 ed to receive the usual tail-pin (not shown) whereby the coupler may be connected to yielding draft rigging mechanism. Near its rear end and between the upper and lower 95 plates 4 thereof, the coupler stem 2 is also preferably provided with a filler or spacing member 6 which is secured in position by means of a vertically extending rivet 7. The member 6 is preferably provided with laterally disposed flanges 8 which serve to 100 properly retain in position the longitudinally extending spring 9 whose forward end bears against the inner end of the slidable frame that carries the transversely extend- 105 ing spring-cups or followers. Slidably mounted between the plates or branches 4 of the coupler stem is a frame which carries followers or spring-cups 10 that, respec- 110 tively, project outwardly in opposite direc- 115 tions beyond the coupler stem. These spring-cups, which are arranged to recipro- 120 cate transversely, are adapted to engage at their outer ends the carry-iron, draft-sills or some other stationary parts of the car. At their inner ends each of the spring-cups 125 is provided with suitable means, such, for example, as the flanges 11, for engaging the

slidable frame to thereby limit the extent of outward movement of separation of said spring-cups. Operatively interposed between the spring-cups is a transversely extending spring 12 which normally maintains them in a position of maximum separation. To prevent this spring from being injured by excessive compression, it is preferred to employ a pin or bar 13 that is loosely mounted within the spring, the pin 13 being of such a length that its ends engage the spring-cups before the spring 12 is compressed solid.

The slideable frame upon which the spring-cups or followers 10 are mounted involves in its construction a bifurcated member 14 having longitudinally extending branches 15 that receive the top and bottom plates 4 of the coupler stem between them. Each of these branches 15 is provided with an opening 16 for the reception of one of the spring-cups 10, such openings 16 being preferably in the form of open-ended slots, as more particularly illustrated in Fig. 6. The inner or free ends of the branches 15 of the bifurcated frame member 14 are preferably connected laterally by a detachable frame member 17 having interlocking engagement with said branches and forming a seat for the longitudinally extending spring 9.

The interlocking engagement of the frame members 14 and 17 is preferably of the nature following: Each of the branches 15 of the bifurcated frame member 14 is preferably provided with a plurality of rearwardly extending projections 18 of rectangular cross section, there being two such projections on each of said branches, one being arranged above the slot 16 and the other below it. The frame member 17 is provided with lugs or projections 19 that abut the free ends of the branches 15 of the bifurcated frame member, the portions 19 of the member 17 being formed with recesses or pockets 20 into which the respective projections 18 are adapted to fit when the frame members 14 and 17 are brought into assembled relation.

While the longitudinally extending spring 9, which bears upon the rear face of the frame member 17 serves to retain the frame members in assembled relation, it is preferred, as a precautionary measure, to employ additional means for this purpose. To this end each of the branches of the bifurcated frame member 14 may be conveniently provided with vertically aligned recesses or key-ways 21, the frame member 17 being provided with correspondingly formed vertically extending slots or key-ways 22. When the frame members are assembled the slots 21 and 22 on the corresponding sides of the frame are in vertical alinement and receive vertically extending keys or fastening devices 23. A transversely extending

cotter 24, which passes through a suitable aperture 25 in the detachable frame member 17 and through each of the keys 23, serves to retain said keys in place.

The frame member 17 is provided at its sides with forwardly extending lugs or flanges 26 which enter the slots 16 in the bifurcated frame member 14, and which, when the parts are in assembled position, have an overlapping engagement with the corresponding flanges 11 upon the rear sides of the respective spring-cups 10. These flanges 26, through their engagement with the flanges 11 of the spring-cups, operate as stops to limit the extent of separation of the spring-cups. Similarly, and for the same purpose, the forward flanges 11 of the spring-cups have overlapping engagement with the inner faces of the corresponding branches 15 of the frame member 14.

The plates or branches 4 of the coupler stem 2 are preferably connected near their outer ends by a rivet 27 which passes through a spacing member or sleeve 28 that is interposed between the plates 4. To permit the frame to slide rearwardly upon the coupler stem 2 in response to turning movements of the coupler head 1 with respect to said stem, the portion of the frame member 14 which connects the branches 15 thereof is recessed or cut away, as best shown at 29 in Figs. 1, 3 and 6. The forward end of the bifurcated frame member 14 extends into a forwardly contracting pocket 30 in the coupler head, said member 14 being formed with vertically extending transverse faces 31 which normally engage corresponding faces 32 on the coupler head 1.

The devices may be assembled as follows: The spring 9 is inserted between the plates 4, 4 of the coupler stem with its rear end bearing upon the filler member or spring seat 6. The frame member 17 is then inserted between the plates of the coupler stem. The transversely extending spring 12, with the pin 13 within it, is then positioned on the coupler stem and the spring-cups 10 are placed on the ends of said spring. The bifurcated frame member 14 is then slid rearwardly between the plates 4 of the coupler stem, the spring-cups 10 entering the slots 16 in the corresponding branches 15 of the bifurcated member, and the inner end of the latter being brought into interlocking relation with the frame member 17. The keys 23 and the cotter 24 are then put in place, after which the coupler head 1 may be brought into proper relation with the coupler stem 2 and connected thereto by means of the pivot pin 3. The coupler head 1 may be then placed in position, and connected to the coupler stem by the pivot pin 3.

The operation of the devices is as follows: When the stem 2 of the coupler is displaced laterally from its normal position

in the longitudinal axis of the car, it moves with it one or the other of the spring-cups 10. During this time the other spring-cup, being in engagement with some stationary part of the car, is prevented from retreating and the transversely extending spring 12 is, therefore, compressed between said spring-cups. When the force that has induced the lateral displacement of the coupler stem ceases to act, the spring 12 will expand, causing the spring-cups 10 to return to normal position thus restoring the coupler to central position. When the coupler head 1 is subjected to a force which causes it to rotate on the pivot pin 3 in either direction from its normal position, one or the other of the shoulders 32 on the coupler head, depending upon the direction of rotation, acts upon the contacting face of shoulder 31 at the forward end of the bifurcated member 14, thus forcing the entire frame to slide rearwardly upon the coupler stem 2. As the longitudinally extending spring 9 bears upon the member 17 which forms the rear end of the frame such spring is compressed by the rearward travel of the frame. The subsequent expansion of this spring restores the frame to normal position, thus also restoring the coupler head to normal or centralized position with respect to the coupler stem 2.

I claim:

1. The combination with a coupler having a head and stem, of a frame mounted upon said stem, and yielding means carried by said frame for centralizing said coupler, said frame involving a bifurcated member having longitudinally extending branches, and detachable means for transversely connecting the free ends of said longitudinally extending branches, said longitudinally extending branches and said detachable means together constituting the boundaries of openings for the reception of said yielding means.

2. The combination with a coupler having a head and stem, of a frame mounted upon said stem, followers carried by and projecting laterally from said frame, and a spring operatively interposed between said followers, said followers and spring constituting yielding means carried by said frame for centralizing said coupler, and said frame involving longitudinally extending portions each having an open-ended slot adapted to receive one of said followers, and detachable means for retaining said followers in assembled positions on said frame.

3. The combination with a coupler having a head and stem, of a frame mounted upon said stem, and yielding means carried by said frame for centralizing said coupler, said frame involving a bifurcated member having longitudinally extending slotted branches.

4. The combination with a coupler having a head and a stem, of a frame mounted upon said stem, and yielding means carried by said frame for centralizing said coupler, said frame involving a bifurcated member having apertures therein through which said means for centralizing the coupler are adapted to extend, and detachable means forming a portion of the boundary of each of said apertures.

5. The combination with a coupler having a head and stem, of a frame mounted upon said stem, and yielding means carried by said frame for centralizing said coupler, said frame involving a bifurcated member having longitudinally extending branches, and detachable means having interlocking engagement with said branches and connecting said branches.

6. The combination with a coupler having a stem and a head pivotally connected to said stem, of a frame slidably mounted on said stem, yielding means carried by said frame for centralizing said coupler, and a longitudinally extending spring operatively interposed between said frame and stem, said frame involving a bifurcated member having longitudinally extending branches and detachable means having interlocking engagement with said branches and forming a seat for said longitudinally extending spring, and said detachable means being by said spring retained in interlocking engagement with said bifurcated member.

7. The combination with a coupler having a stem and a head pivotally mounted on said stem, of a frame slidably mounted on said stem, yielding means carried by said frame for centralizing said coupler, and a spring operatively interposed between the rear end of said frame and said stem, said frame involving separable transversely interlocked members which may be disengaged by a relative movement in the direction of length of said stem, and detachable means for retaining said frame members in assembled relation.

8. The combination with a coupler having a head and stem, of a frame mounted upon said stem, and spring controlled means carried by and projecting from said frame for centralizing said coupler, said frame involving a bifurcated member having longitudinally extending branches, a detachable member having interlocking engagement with each of said branches, and keys for connecting said bifurcated member and said detachable member, said bifurcated member and said detachable member being provided with aligned keyways.

9. The combination with a coupler having a stem and a head pivotally mounted on said stem, of a frame slidably mounted on said stem and engaging said head, a longitudinally extending spring operatively inter-

posed between the rear end of said frame and said stem, flanged followers carried by said frame and projecting laterally therefrom and adapted to reciprocate laterally with respect thereto, and a transversely extending spring interposed between said followers, said frame involving a bifurcated member having longitudinally extending slotted branches, a detachable member hav-

ing interlocking engagement with said branches and forming a seat for said longitudinally extending spring, a plurality of keys for connecting said bifurcated members and said detachable member, and means for maintaining said keys in assembled relation.

WILLIAM McCONWAY, JR.
